UNITED STATES PATENT OFFICE.

RALPH EMERSON, JR., AND F. GRAHAM, OF ROCKFORD, ILLINOIS,
ASSIGNORS TO RALPH EMERSON, JR.

IMPROVEMENT IN MOWING-MACHINES.

Specification forming part of Letters Patent No. 34,180, dated January 14, 1862.

To all whom it may concern:

Be it known that we, RALPH EMERSON, Jr., and FREEMAN GRAHAM, both of Rockford, in the county of Winnebago and State of Illinois, have invented a certain new and useful Improvement in Mowing-Machines, of which the following is a full, clear, and exact description, reference being had to the accompanying drawings, which make part of this specification, and in which—

Figure 1 represents a view in elevation of a mowing-machine embracing our improvement as seen from the gearing or stubble side of the machine, the black lines representing the attitude assumed by the several parts when the finger-beam rests upon the ground, and the red lines the relative position of the parts when the finger-beam is elevated to its highest point. Fig. 2 represents a similar view of the same as seen from the divider side of the machine, with the bearing-wheel removed from the axle; and Fig. 3 represents a plan or top view of the same.

Our invention relates to that class of mowing-machines which contain the following among other features, vizi: first, a gearing-frame oscillating upon a fulcrum in rear of the cutting apparatus; secondly, a finger-beam rigidly secured to the front edge of the gearing-frame, so as always to remain in the same horizontal plane with it; thirdly, a tongue connected to the frame by a flexible joint in or near the line of the cutting apparatus; and, fourthly, an arm or bar rigidly secured to the tongue and extending backward over the frame, said bar being connected with a hand-lever turning on a fulcrum near the driver's seat to assist in the adjustment of the cutting apparatus; and our improvement consists in a novel combination of the various parts, whereby we are enabled to produce a simple, compact, and efficient machine, well adapted to the varying circumstances under which a mower is required to operate.

In the accompanying drawings, the frame A is represented as being of a trapezoidal figure, with its front and rear edges parallel, and its inner side inclined. It is wider in front than in rear, and rests mainly upon a large wheel, B, which is also the driving-wheel. A finger-beam, D, is rigidly secured to the front edge of the frame A, and projects on one side there-

of. The finger-beam in this instance is composed of two plates of metal, the upper one of which is flat, while the under one is L-shaped and bent up at the back to form a ledge of the depth required for the thickness of the beam. The guard-fingers are inserted between the plates, and the whole securely riveted together, thus forming a light but strong beam.

The machine is drawn by means of a hinged tongue, E, attached to the shoes d (which may form part of the finger-beam) by means of a pin, d', which permits the tongue to play freely up and down, but not laterally.

A bearing or supporting wheel, C, is mounted upon the inner side of the main frame, and turns upon a crank-axle, e, which has its bearings in journals in or very nearly in the same axial plane as the driving-wheel B. This axle has also a pivotal movement in its bearings. A hand-lever, G, is rigidly secured upon the inner end of the crank-axle e in such manner that when the lever is in a vertical position the bent part of the axle shall be horizontal, or nearly so, as shown in the drawings. The lever extends above and near to the driver's seat H.

An arm or bar, F, is rigidly secured to the rear end of the tongue E, and projects backward over the frame. To the under side of this bar a bracket, f, is secured. This bracket forms an inclined plane or way, upon which a friction-roller on the hand-lever G travels to raise and lower the machine. The arm and standard are held in contact by means of a guide-plate, g, on the side of the standard or lever-handle G.

The driver's seat H rests upon springs secured to a frame, h, composed of two inclined beams inserted into the frame and firmly connected at top. The position of this seat is such as very nearly to balance the weight of the driver (when in his seat) upon the axis of the driving-wheel. A foot-board, I, is also secured upon the front bar of the frame h, in front of the driving-wheel.

The other parts of the machine may be constructed in any of the usual well-known ways; but as they form no part of the subject-matter herein claimed the details of their construction are omitted.

The operation of the machine is as follows: When the parts assume the attitude shown in

the drawings, the weight of the machine rests upon the driving-wheel and upon the finger-beam, which latter runs upon the ground. In this position the bearing-wheel C rests lightly upon the ground, but supports no part of the weight of the machine, while the hinge by which the tongue and frame are connected permits the machine to oscillate freely upon its wheel in order that the cutting apparatus may conform closely to the inequalities of the surface of the ground. To raise the cutting apparatus, the driver seizes the upper end of the hand-lever G and pushes it forward into the position shown by the red lines in the drawings. As the lever descends the friction-roller upon its side acts upon the under side of the bracket f, and as both the lever and arm are rigidly secured to the crank-axle and tongue, respectively, while the joint is flexible, the cutting apparatus is gradually raised until the parts assume the position shown by the red lines in the drawings. The forward movement of the hand-lever G depresses the journal of the bearing-wheel C, and thus causes a portion of the weight of the machine to rest upon the wheel, so that the entire weight, except that portion which is borne by the team, rests upon the wheels B and C. The lever may be held in its extreme forward position by means of a notch in the lower extremity of the bracket f, or it may be held in any intermediate position desired by the simple pressure of the hand or foot of the driver. In this latter

case the parts would resume their original attitude as soon as the lever was released by the withdrawal of his foot or hand, while in the former event the lever would still be held by the notch until released by the driver. As the cutters are raised the driver's seat is carried farther back of the axis of the wheels, which movement facilitates the raising of the machine.

It will readily be perceived from this description that both the crank-axle c and the inclined way or bracket f are essential to the proper working of the machine.

We do not claim, broadly, under this patent the use of a crank-axle, nor of a flexible joint in the line of the cutting apparatus; but,

Having thus fully described the construction and operation of our improved mowing-machine, what we do claim therein as new, and desire to secure by Letters Patent, is—

The combination of the bent axle c and hand-lever G with the arm F and bracket f, when arranged for joint operation relatively to each other and to the machine, substantially in the manner herein described, for the purpose set forth.

In testimony whereof we have hereunto subscribed our names.

RALPH EMERSON, JR.
FREEMAN GRAHAM.
